(57) **CLAIM**

I claim the ornamental design for a folding magnifier, as shown and described.

DESCRIPTION

FIG. 1 is a first perspective view of the folding magnifier with the lense retracted;

FIG. 2 is a second perspective view of the folding magnifier with the lense retracted;

FIG. 3 is a right side view of the folding magnifier with the lense retracted;

FIG. 4 is a front side view of the folding magnifier with the lense retracted;

FIG. 5 is a top view of the folding magnifier with the lense retracted;

FIG. 6 is a left side view of the folding magnifier with the lense retracted;

FIG. 7 is a rear side view of the folding magnifier with the lense retracted;

FIG. 8 is a bottom view of the folding magnifier with the lense retracted;

FIG. 9 is a first perspective view of the folding magnifier with the lense extended;

FIG. 10 is a second perspective view of the folding magnifier with the lense extended;

FIG. 11 is a right side view of the folding magnifier with the lense extended;

FIG. 12 is a front side view of the folding magnifier with the lense extended;

FIG. 13 is a top view of the folding magnifier with the lense extended;

FIG. 14 is a left side view of the folding magnifier with the lense extended;

FIG. 15 is a rear side view of the folding magnifier with the lense extended; and,

FIG. 16 is a bottom view of the folding magnifier with the lense extended.

1 Claim, 7 Drawing Sheets
